INDICATING CUTOUT

Richard W. Barnitz, Parkersburg, W. Va., assignor to Porcelain Products, Inc., Findlay, Ohio, a corporation of Delaware

Application February 18, 1941, Serial No. 379,507

9 Claims. (Cl. 200—114)

The invention of which the following is a description in detail, relates to indicating cut-outs used on electrical transmission lines of relatively high voltage. Such transmission lines must be provided with fuses conveniently placed along the overhead lines or in advance of connected transformers. When an emergency or abnormal condition causes one of these fuses to open the circuit, the fact must be made evident to a line-man standing on the ground. When the fuse gives an indication of having burned out, it is then necessary for it to be replaced with a minimum of danger to the workman. At the same time it is desirable to insure the normal fuse from accidental or inadvertent dislodgment and from break-down caused by mechanical strain.

One of the objects of my invention is to provide a cut-out in which the fuse tube or holder will drop out of the housing and indicate disconnection of the circuit as soon as the fuse link or wire has melted.

It is a further object of my invention to locate such a fuse-holder entirely upon the cover of the cut-out housing so that the act of opening the cover will remove the fuse-holder from contact with the transmission line.

It is a further object of my invention to block the removal of the fuse-holder from the cover until the latter has been opened regardless of whether or not the fuse link has been broken.

In particular my invention carries out the above objects by providing a fuse-holder which must be partially rotated for removal from the cover.

An additional object of my invention is to mount a fuse-holder upon the inside face of the housing cover with certainty in the operation of the mechanical details of the latch.

A further object of my invention is to reduce the strain which ordinarily attends the engagement between the latch mechanism and the normally operating fuse link.

Other objects of my invention will be clearly understood from the following description as illustrated for the purpose of example by the preferred form of the invention shown on the accompanying drawings in which

Fig. 1 is a side elevation partly in section of the improved electrical cut-out;

Fig. 2 is a front elevation of the inside face of the door and the fuse-holder carried thereby;

Fig. 3 is a top plan view of the same;

Fig. 4 is an enlarged transverse section taken on the line 4—4 of Fig. 1 and

Fig. 5 is a fragmentary vertical section on line 55

5—5 of Fig. 2 showing the method of pivotally supporting the cover.

By way of example, I have shown the preferred form of my invention as applied to an enclosed or housed electrical cut-out or fuse mechanism. Such devices are usually provided with an attached fixture 5 to which a housing 6 is bolted in the usual manner. The fixture 5 permits the housing to be mounted upon a transmission pole or cross arm. The housing is made of suitable electrical porcelain in a manner well known in the art. Housings of this type have overhanging tops 7, the front is open and the bottom also is open between the lower extensions of the side walls 8, 8. These side walls in an intermediate portion are brought closer together as shown at 9 in Fig. 4 to diminish the width of the opening for a purpose which will appear later.

The inside of the housing also has barriers or baffles 10, 10 as is customary with devices of this character.

Above the barriers 10, 10 the housing is recessed to receive an upper terminal 11. This terminal is anchored by means of spring fingers 12 and 12a respectively to the top and sides of the inner walls of the housing. The terminal 11 carries a contact 13 consisting of a laminated flat spring, one end of which 14 is free and the other end riveted as at 15 with the spring fingers 12 to the terminal casting 11. A conductor 16 passes through a sleeve in the top of the terminal 11. Below the barriers 10, 10 the back wall of the housing is also recessed to form a seat for a lower terminal 17. This lower terminal is also anchored by the spring fingers 18 in recesses of the side walls of the housing (see Fig. 4). This is similar to the anchorage of spring fingers 12 to the sides of the housing walls. A contact 19 formed of laminated flat springs is riveted to the lower terminal 17 by rivet 20 and has its free end 21 bent backward to form a resilient contact. A second conductor 22 passes transversely through the housing and is anchored in a sleeve forming part of the lower terminal 17.

A cover or door 21 also of porcelain "Bakelite" or similar material is provided with a narrow lower portion 28 which has a transverse opening. This opening has a transverse hinge pin 24 centered by the enlargements 25. The pin 24 is eccentrically mounted in two guide plates 23 on opposite sides of the door portion 28. The ends of pin 24 rest in stirrups 26, 26 anchored on the inner faces of the side walls 8, 8. The stirrups 26, 26 have upper front openings 26a

and are inwardly offset at their upper ends to form retainers 26^b. Retainers 26^b overhang the plates 23 preventing the pin ends 24 from rising in the stirrups or being removed through the openings 26^a except when the door 27 is inverted.

The upper outer portion of the door is shaped to provide a finger hold 29.

The inner surface of the door is equipped to support a fuse-holder, maintaining electrical connection between it and the spring contacts 14 and 21 when the door is in the closed position by permitting the fuse-holder to drop out of contact with the members 14 and 21 into visible indicating position with the door closed. The retaining means on the door prevents complete separation of the fuse-holder from the door until the fuse-holder has been given a partial rotation.

To accomplish this purpose a collar 30 is bolted to the upper portion of the door. The collar has an annular opening 31 which will receive the upper ferrule of the fuse-holder. The collar is extended in front and tapered downwardly to provide an extension or projection 32. This projection rests against the upper terminal 11 and forms a stop for the door in its closed position. While some of the current may pass through the projection 32 and to the upper ferrule of the fuse-holder, principal reliance is made on the spring contact 41 for the dual purposes of maintaining electric contact and assisting in the dropping movement of the fuse-holder when released by the latch.

The lower portion of the door beneath the collar 30 carries a retaining sleeve 33. This sleeve is bolted to the door as shown in Figs. 1 and 2 and has its main portion slotted vertically or longitudinally as at 34. It thus provides a cylindrical passageway to retain the fuse-holder but permits it to drop down when the fuse is broken.

Beneath the retaining sleeve 33 the inner face of the door is recessed as at 35. A flat spring 36 is held by the door and at its lower free end has an upwardly directed catch 37. The spring holds the catch 37 normally out of the recess 35 into which it is pressed during the operation of assembling the fuse-holder on the door.

The fuse-holder 38 is provided in the customary form as a hollow tubular member of fiber, plastic or similar material. It has an upper metallic contacting ferrule 39 which is screw-threaded to receive the cap 40 by which the upper end of the fuse wire is attached. The lower end of the ferrule is enlarged as shown at 41 and carries a radially extending lug or stop 42. It is possible to omit the enlargement 41 if convenient. If it is used it will of course be less in diameter than the inner passageway of the retaining sleeve 33. The stop 42, however, extends far enough out to strike the upper face of the retainer 33.

The fuse-holder 38 has a lower ferrule 43 of metal and forming the support of a binding post 44. A knurled nut 45 on the post 44 serves for the attachment of the lower free end of the fuse wire 46.

The lower ferrule is extended on one side to form the projection 47 through which the transverse pivot pin 48 runs. A lever 49 is loosely pivoted on pin 48 and held in position by any suitable means. One end of the lever 49 extends across the end of the fuse tube in the form of a hollow ring around which the fuse wire 46 is wrapped before being attached to the binding post 44.

The opposite end of the lever 49 is in the form

of a latch 50. This latch 50 is formed to fit the catch 37 with a slight inclination in the plane of engagement as shown in Fig. 1. This insures the holding of latch 50 by catch 37 under the spring pressure from contacts 14 and 21 and prevents failure by reason of inadvertent disengagement. It will also be seen that this method of engagement places the tension spring 36 on the door and away from the movable fuse tube.

The lower ferrule 43 has a longitudinal rib, flange or web 51. This slides loosely in the slot 34 of the retainer 33 and takes the position shown in Figs. 1, 2 and 4. The rib 51 terminates in a transverse contact bar 52 of substantial extent. This gives an extended bearing transversely against the free end of the spring contact 21.

The use of lever 49 free from any spring permits the assembly of the latch 50 and the fuse 46 in operative position without imposing any tension on the latter other than that resulting indirectly from springs 12 and 21 and the weight of the fuseholder itself. The relative length of the lever 49 compared with the latch 50 increases the strain carried by the latch but decreases the strain which may be imposed by the relatively longer lever 49 on the fuse link 46 thus the latter is protected against failure other than that which may be caused by abnormal circuit conditions.

The fuse tube thus arranged is mounted in position on the door by first sliding the ferrule 39 through the retainer 33 with the stop 42 passing through the slot 34. The fuse tube is then given a partial rotation, such as 120° indicated in Fig. 3 as an example, and this brings the rib 51 in line with the slot 34. The fuse tube as it is raised brings the latch 50 against the catch 37 forcing the latter back and releasing it into locking engagement as shown in Fig. 1.

The assembly having been completed with the door in open position, it is then closed bringing the projection 32 against the upper terminal 11. In this movement the spring contact 14 is compressed against the cap 40 and the spring contact 21 is compressed by the contact bar 52 against which it is maintained with an extended engagement.

Normal current then passes from one conductor through the adjacent spring contact, the fuse link and finally to the other conductor. On the event of an abnormal flow of current beyond the limit provided by the fuse link, the latter fuses and releases the lever 49 for pivotal movement. Pressure from the contacts 14 and 21 swing latch 50 away from catch 37 thus permitting the fuse tube to drop by the pressure of the springs and its own gravity into the dotted line position shown in Fig. 1. Here the stop 42 comes to rest upon the upper face of the retainer 33. The fuse tube may then be given a partial rotation to bring the stop 42 in line with the slot 34 through which it may be drawn to completely release the fuse-holder.

The inadvertent removal of the fuse-holder is prevented by the restricted portions of the side walls 9 which prevent the rotation of the fuse-tube to the degree required to bring the stop 42 in line with the slot 34.

I have shown my invention as embodied in the device above described but reserve the right to make such changes in proportions, dimensions and materials as is provided by the scope of the following claims.

What I claim is:

1. An enclosed cut-out having a bottomless housing and line terminals therein, spring con-

tacts on said terminals, a door hinged to the housing, a collar on the door, a sleeve on the door beneath the collar, a spring catch on the door, a fuse-tube slidable vertically through said sleeve and collar, and a fuse-controlled latch pivoted on the lower end of the fuse-tube, said tube being pressed by the spring contacts downwardly against the catch when the door is closed.

2. An enclosed cut-out having a bottomless housing and line terminals therein, spring contacts on said terminals, a door hinged to the housing, a collar on the door, a sleeve on the door beneath the collar, a spring catch on the door, a fuse-tube slidable vertically through said sleeve and collar, a latch pivoted on the lower end of the fuse-tube, and a fuse link having its free end passed around the latch and anchored with the latch extended for engagement with said catch.

3. An enclosed cut-out having a bottomless housing and line terminals therein, a door hinged to the housing, a collar on the door, a sleeve on the door beneath the collar, a spring catch on the door, a fuse-tube slidable vertically through said sleeve and collar, a lever pivoted on the tube, a binding post mounted on the tube, a fuse link having its free end passed around the lever and held by said binding post and a latch on the end of the lever for engagement with said catch.

4. An enclosed cut-out having a bottomless housing and line terminals therein, spring contacts on said terminals, a door hinged to the housing, a collar on the door, a sleeve on the door beneath the collar, a fuse-tube slidable vertically through said sleeve and collar, means for releasably latching the tube in operative position, and a radially extending stop on the tube for arresting the downward sliding movement of the tube through the sleeve when the tube is unlatched, said sleeve being slotted longitudinally to provide a limited angular clearance for controlled passage of the stop therethrough.

5. An enclosed cut-out having a bottomless housing and line terminals therein, spring contacts on said terminals, a door hinged to the housing, a collar on the door, a sleeve on the door beneath the collar, a fuse-tube slidable vertically through said sleeve and collar, means for releasably latching the tube in operative position and a radially extending stop on the upper ferrule of the fuse-tube, said sleeve being slotted longitudinally for an angular extent sufficient to provide clearance for the controlled passage of the stop therethrough.

6. An enclosed cut-out having a bottomless housing and line terminals therein, spring con- 55

tacts on said terminals, a door hinged to the housing, a collar on the door, a sleeve on the door beneath the collar, said sleeve being longitudinally slotted, a fuse-tube slidable vertically through said sleeve and collar, means for releasably latching the tube in operative position, upper and lower ferrules on the tube, a narrow longitudinal rib on the lower ferrule, and a stop on the upper ferrule narrower than the slot in said sleeve, said stop being angularly displaced with respect to said rib.

7. An enclosed cut-out having a bottomless housing and line terminals therein, spring contacts on said terminals, a door hinged to the housing, a collar on the door, a sleeve on the door beneath the collar, said sleeve being longitudinally slotted, a fuse-tube slidable vertically through said sleeve and collar, means for releasably latching the tube in operative position, a ferrule on the tube, a longitudinal rib on the ferrule slidable through the slot in the sleeve and a relatively wide extension on the rib engaging one of said spring contacts.

8. An enclosed cut-out having a bottomless housing and line terminals therein, spring contacts on said terminals inwardly projecting portions in the lower side walls of said housing, a door hinged to the housing, a collar on the door, a sleeve being longitudinally slotted, a fuse-tube slidable vertically through said sleeve and collar, means for releasably latching the tube in operative position, a ferrule on the tube, a longitudinal rib on the ferrule and an extension on said rib occupying the major amount of the space between said inwardly projecting portions of the side walls.

9. An enclosed cut-out having a bottomless housing and line terminals therein, spring contacts on said terminals, inwardly projecting portions in the lower side walls of said housing, a door hinged to the housing, a collar on the door, a sleeve on the door beneath the collar and opposite said inwardly projecting portions of the side walls, said sleeve being longitudinally slotted, a fuse-tube slidable vertically through said sleeve and collar, means for releasably latching the tube in operative position, an upper ferrule on the tube, a stop projecting radially from the ferrule, a lower ferrule on the tube, a longitudinal rib on the ferrule radially spaced from said stop, said rib being slidable through the slot of the sleeve and an extension on said rib occupying the major amount of the space between said inwardly projecting portions of the side walls.

RICHARD W. BARNITZ.
